UNITED STATES PATENT OFFICE

CLINTON E. LARRABEE, OF BINGHAMTON, NEW YORK, ASSIGNOR TO INTERNATIONAL TIME RECORDING COMPANY OF NEW YORK, OF ENDICOTT, NEW YORK, A CORPORATION OF NEW YORK

SYNCHRONIZING MECHANISM FOR SECONDARY CLOCKS

Application filed April 3, 1929. Serial No. 352,234.

This invention relates to electrical secondary clocks which are driven and maintained in synchronism by electrical energy controlled by both a master clock and the secondary clock.

It deals particularly with a system in which the secondary clock may receive electrical impulses over either one of two lines and make use of them according to its chronological condition of agreement or disagreement with a master clock which sends out the electrical impulses and causes the secondary clock to be stepped ahead if it be slow or to stop altogether if it be fast for a period of time equal to the amount that it is fast and then resume normal operation.

The present invention concerns the provision of a new and efficient automatic switching mechanism for use in a synchronized clock system of the type indicated.

The improved switching mechanism of the present invention forms that part of the synchronizing control operated by the secondary clock itself for use in connection with such a system as shown in U. S. patent to Bryce 1,687,491. In this system two wires, which may be distinguished as the A wire and the B wire are connected to the impulse devices of a master clock. During the greater portion of each hour minute impulses are sent over both wires. At the beginning of a synchronizing period usually the last fifteen minutes of each hour, the B wire is automatically disconnected from the impulse devices and receives no minute impulses until the end of the synchronizing period when it is automatically reconnected in circuit, receiving its first minute impulse on the even hour.

The A wire receives minute impulses continually and, in addition, during the last minute of the synchronizing period receives a series of more rapid impulses whose function is to step ahead any secondary clocks which may be slow. The switching mechanism controlled by the secondary clock switches its operating magnet from one wire to the other. When the secondary clock registers the last minute of the synchronizing period, that is, the fifty-ninth minute after the hour its switching mechanism automatically connects

its operating magnet to the B wire. Some time later usually about fifteen minutes the operating magnet is switched back to the A wire. It will thus be understood that any secondary clock which registers slow will remain on the A wire during the synchronizing period until it receives enough of the fast impulses during the last minute of the hour to bring its registration to fifty-nine minutes after the hour when it is automatically shifted to the B wire. Any secondary clock which registers fast will shift to the B wire when it registers 59 minutes after the hour and as the B wire receives no impulses during the synchronizing period such clocks will not move until the end of the period. When the B wire receives its first minute impulse on the even hour all secondary clocks step off in unison and register the even hour. This system forms per se no part of the present invention and need not be described in detail but the switching operations just explained should be borne in mind in connection with the following detailed description of the secondary clock switching mechanism.

Referring now to the drawings:

Fig. 1 shows a rear view of the secondary clock and the new automatic switching mechanism;

Fig. 2 is a side elevation of the mechanism as shown in Fig. 1;

Fig. 3 is an isometric view of the switching mechanism to an enlarged scale;

Fig. 4 indicates the connection of the actuating magnet with the controlling circuits.

The secondary clock mechanism as illustrated in the accompanying drawings is mounted upon a front plate 2 and a rear plate 3 connected with each other by cross rods 4. Upon the plate 1 is mounted an electromagnet consisting of two magnet cores 5 and their associated magnet coils 6. The hands 8 and 14 of the clock are driven by the usual gearing from the ratchet wheel 7 which is actuated by magnets 6 as will be explained. The ratchet wheel 7 is actuated whenever the operating magnet receives an impulse and is fixed to a shaft 9 journaled in the plates 2 and 3. At the opposite sides of said shaft is fixed the minute hand 8. The usual well

known gear train reduction is provided between the minute hand 8 and the hour hand 14 including the gear 13 fast to a sleeve upon shaft 9 which sleeve carries the hour hand 14.

5 The armature 23 of the electromagnet is a rectangular block mounted between two disks 43 and the assembly is journaled in a swingable frame. The frame consists of a cross piece 21 joining two vertical arms 17 and 18 which extend on opposite sides of the electromagnet and are pivoted on studs 15. The holes in the arms to accommodate the studs are slightly enlarged to permit lost motion and the arms and the whole swingable frame 15 is pulled down by springs 19 anchored to the arms 17 and 18 and to clips on the studs 15. This seats the disks 43 firmly on a horizontal supporting plate 28 but permits them to roll thereon.

20 A curved pin 27 is fixed to the mid section of the armature and extends through a hole in plate 28. A spring 24 holds the swingable frame to the right, with respect to Fig. 2, with the block armature 23 at an angle to the 25 vertical and the end of pin 27 engaged in the hole in plate 28. On energization of the magnet armature 23 tends to move into the most intense part of the magnetic field and owing to its constraint by the disks 43 and pin 27 causes the disks 43 to roll on the plate 28 to the position shown in Fig. 2. This rolling of the disks, of course, causes the arms 17 and 18 to rock slightly in a counterclockwise direction about the studs 15.

35 The rocking movement of the frame, as just described, operates a pawl to stop the ratchet wheel 7. A stud shaft 29 is supported on a suitable bracket on front plate 2 and a plate 30 is pivotally mounted thereon. This 40 plate is slotted at 33 to receive a pin 34 on arm 17. In normal rest position when arm 17 is held to the right in Fig. 2 by spring 24, pin 34 depresses plate 30 and an extension 30a moves between the ratchet teeth of wheel 7 and holds the parts firmly in position. A 45 plate 31 has a bifurcated end which straddles shaft 29 and a pin 32 fast to plate 30 and extending through a hole in plate 31 holds these plates together. The end of plate 31 is bent sideways extending through a slot in plate 50 and is formed with teeth to act as a pawl coacting with the ratchet teeth of wheel 7. A spring 35 on pin 32 resiliently presses the teeth in the bent end of plate 31 against the 55 ratchet teeth.

When magnet 6 is energized causing arm 17 to rock counterclockwise to the position shown in Fig. 2, pin 34 coacting with the curved edge of slot 33 raises plates 30 and 60 31 moving extension 30a sidewise out of engagement with the ratchet teeth and causing the pawl teeth in plate 32 to click over ratchet wheel 7 for the space of one tooth. When the magnet is deenergized spring 24 returns 65 arm 17 to normal position and plates 30 and

31 are lowered stepping ratchet wheel 7 the space of one tooth and again locking it through extension 30a. This mechanism is fully described and claimed in copending application Serial No. 313,662 filed October 20, 70 1928.

The synchronizing contact mechanism forming the subject matter of the present invention is carried by a plate 44 fastened to the clock frame at 45 and 46. An insulating plate 47 fixed to plate 44 has a contact block 48 connected to one terminal of the electromagnet 6 and contact elements 49, 50 and 51 of which 51 is connected to the other terminal of magnet 6. The contacts 49 and 50 are provided with spaced fingers 49' and 50' and a spring finger 51' of contact 51 plays between them so that it may contact with either. A stud 52 on plate 44 carries a rotatable sleeve 53 to which is fixed a rod 54. Pivoted on this rod is a frame 58 having end extensions 56 and 57. Extension 57 is bifurcated to receive an insulating section on contact finger 51' so that when the frame is rocked about rod 54 this finger will alternately engage fingers 49' and 50'. The end piece 56 has two ears 59 and 60 and a center extension 73. Cams 71 and 72 mounted on shaft 9 and thus operated by the clockwork, control the rocking of the frame 58 and a spring 75 pulls down on rod 54 so that ears 59 and 60 engage cams 71 and 72, respectively.

Cam 72 is of larger diameter than cam 71 and consequently the downward pull on rod 54 causes the frame to rock so that bifurcated extension 57 forces contact finger 51' into engagement with contact finger 50'. The cam 72 is provided with a step 77 and when this comes under ear 60 the downward pull of spring 75 on rod 54 causes the frame 58 to shift so that bifurcated end 57 shifts contact finger 51' out of engagement with finger 50' and into engagement with finger 49'. Somewhat later a step 78 on cam 71 comes under ear 59 and the frame 58 rocks back so that contact finger 51' again engages contact 50'. The periods during which the contact finger 51' is in engagement with fingers 49' and 50' may be selected as desired but ordinarily they will be selected for the system as previously mentioned.

The circuit connections for a system such as disclosed in the Bryce Patent 1,687,491 previously mentioned is illustrated in Fig. 4. The A wire receives an impulse every minute and a series of fast impulses during the last minute of each hour. The B wire receives minute impulses from the even hour to forty five minutes thereafter. The C wire forms a common return. Owing to the configuration of the cams 71 and 72 the contacts 50 and 51 are in engagement during the greater portion of each hour thus connecting magnet 6 to the A wire. When the secondary clock registers fifty-nine minutes after the

hour contact 51 shifts into engagement with contact 49 thus connecting the magnet 6 to the B wire and this connection persists until some time after the even hour whereupon the 5 magnet 6 is shifted back to the A wire. The synchronizing of the secondary clocks will be understood from the explanation of the system previously given.

While there has been shown and described 10 and pointed out the fundamental novel features of the invention as applied to a single modification it will be understood that various omissions and substitutions and changes in the form and details of the device illustrated and in its operation may be made by those skilled in the art without departing 15 from the spirit of the invention. It is the intention therefore to be limited only as indicated by the scope of the following claims:

20 1. In a secondary clock, a driving magnet controlled by an actuating circuit, a driving shaft carrying the hands of the clock on its one end and a pair of stepped cams on its 25 opposite end, said shaft being actuated by said magnet, a pivotally mounted rod arranged parallelly to the plane of said cams, a switching element, pivotally supported by said rod and connecting said driving magnet with different lines of said actuating circuit, said switching element having wing portions on opposite sides of the axis of said rod, each wing portion riding upon an associated stepped cam to pivot said switching element 30 into different switching positions by the steps of said cams.

35 2. In a secondary clock, an automatic switching mechanism including a pivotally supported shaft, a switching element rotatably supported by said shaft and a switching of clock controlled cam elements coacting with said switching element to pivot said switching element about said shaft into different switching positions.

40 3. In a secondary clock, an automatic switching mechanism including a pivotally supported shaft, a switching element rotatably supported by said shaft and a switching blade controlled by said switching element, a pair of clock controlled cam elements arranged parallelly to said shaft and coacting with the switching element supported by said shaft to pivot said element about said shaft 45 into different switching positions.

45 5. In a magnetically driven secondary clock, a plurality of terminals of different feed lines, a terminal for a common back line, said terminal being connected with said magnet and a switching element under the control 50 of said clock mechanism to selectively connect either one of said feed line terminals with said magnet, said means comprising a pair of stepped cams, a pivotally mounted rod extending parallelly to the plane of said cams, a bar having rectangularly bent termi-

nal portions supported by said rod, one of said terminal portions having a bifurcation guiding said switching element and the opposite bent terminal portion having a finger passing between said cams and a wing portion on each side of said finger, each wing portion riding on the surface of an associated cam.

5. A mechanism according to claim 4 70 wherein means are provided to engage said wing portions resiliently with said cams to effect tilting of said bar upon dropping of a wing off a step of its associated cam.

6. In a secondary clock, an automatic switching mechanism including in combination, a pivotally mounted rod, a switching element tiltably supported by said rod, a plurality of stepped cams controlled by the clock mechanism the steps of said cams coacting with said switching element to tilt the same alternately in opposite directions upon subsequent coaction with steps of different cams.

7. In a secondary clock, an automatic switching mechanism including in combination, a pair of cams mounted on the driving shaft of said clock each cam having a step, said steps being displaced from each other for a predetermined amount, a pivotally mounted rod extending approximately tangentially to said cams, a switch element comprising a plate having rectangularly bent terminal portions each having a hole through which said rod passes to support said switch element in proximity of the ends of said rod, one terminal portion having a bifurcation, an insulating piece carrying a switch blade said insulating piece being guided by said bifurcation, and the opposite terminal portion having two wings on opposite sides of said rod, each wing riding upon a cam, and a finger integral with said portion to limit tilting movement of said switch element by coacting with either one of said cams, and a spring element coacting with said rod to urge the wing portions of said switch element into riding engagement with said cams and tilt said switch element upon dropping of a wing off a step of the cam.

100 8. In testimony whereof I hereto affix my 105 signature.

CLINTON E. LARRABEE.
